REVERSIBLE CRAVAT

Gilles Grielen, 26 Rue Roussy, Lyon, France

Filed May 7, 1963, Ser. No. 74,786

Term of patent 14 years

Claims priority, application France Nov. 15, 1962

(Cl. D3—16)

FIG. 1 is a front perspective view of a reversible cravat of this invention showing the front of one portion and the rear of the other portion;

FIG. 2 is a rear perspective view thereof; and

FIG. 3 is a fragmentary perspective view of the ends of the cravat showing how they appear when viewed from a position on the right side of FIG. 1.

The novel appearance of the cravat of the present invention is characterized in that continuous cross-stitching is disposed along one side and the bottom of the cravat.

I claim:

The ornamental design for a reversible cravat, as shown and described.
